SWITCH CHAMBER FOR ALTERNATING CURRENTS

André Latour, Grenoble, France

Application September 25, 1946, Serial No. 699,185
In France October 3, 1945

7 Claims. (Cl. 200—150)

1

This invention relates to circuit interrupters of the oil blast type having pressure pots provided with means for regulating the discharge of arc extinguishing fluid across the arc.

An object of the invention is to provide interrupters in which the discharge of arc extinguishing fluid across the arc is reduced to a minimum when the current itself is at a maximum or in the vicinity of its maximum and increased to a maximum when the current value approximates zero.

Another object of this invention is to provide interrupters in which the pressure pot is provided with pressure controlled discharge means, adapted to be opened in order to prevent the blast of arc extinguishing fluid across the arc, whilst the current is at a maximum or the vicinity of the maximum, and to be closed whilst the current approximates zero in order to cause the blast of arc extinguishing fluid.

Another object of this invention is to provide interrupters in which the pressure pot is provided with blast passages, the opening of which or the efficiency of which is prevented or reduced or delayed whilst the current is at a maximum and increased or accelerated when the current approximates zero.

According to an embodiment of my invention, I provide a pressure pot which is provided with a chamber performing a to and fro movement in axial direction—that is the direction of the movement of the movable contact rod—under the pressure developed by the arc which remains in the pressure pot until it is extinguished.

Such movable chambers are known in combination with interrupters of the type commonly called "expansion interrupters," in which the chambers with their springs are constructed so as to let a strong pressure develop before a large discharge aperture is opened.

According to my present invention, such chambers are combined with blast interrupters and are constructed so as to open immediately so as to prevent or reduce any rise of pressure, whilst the current is at its maximum, and to be closed when the current decreases to the vicinity of zero.

Simultaneously, the to and fro movement of the chamber is utilized to prevent, delay or reduce the opening or the efficiency of the blast apertures of the pressure pot during the first part of the movement, and to accelerate the opening or increase the efficiency of the same during the second part of the movement.

Further features of the invention will be more specifically pointed out in the following disclosure.

2

sure in which reference is had to the accompanying drawing, both being given by way of example and having no limiting character. Preferably but not necessarily, the disclosure and the drawings relate to devices in which pressure is provided by means of a partly or wholly insulating liquid, but it is to be understood that within the scope of the invention said pressure may be obtained by means of an outside source of pressure gas or created by a solid substance which will be gasified by the action of the electric arc.

In the drawings:

Figure 1 is an axial sectional view of a switch according to the invention with transversal blow-out;

Figure 2 shows the switch according to Fig. 1 at the moment when the pressure generated by the arc reaches its maximum;

Figure 3 is an axial sectional view of a switch according to the invention with axial blow-out;

Figure 4 illustrates a switch according to the invention in which the arc is choked by the action of a jet of insulating fluid;

Figure 5 is an elevational view of a particular embodiment of the chamber fastening means, and

Figure 6 is a plan view of the arrangement shown in Fig. 5.

Referring now to Fig. 1, the stationary contact 1 and the movable contact 2 are located in a chamber 3 provided with a row of orifices situated one above the other. The relief orifice 5 is located adjacent to the fixed contact 1. In the position shown, where the pressure prevailing within chamber 3 is assumed to be low or nil, the orifice 5 is closed by a fixed piston 4 in which the contact 1 is accommodated. The blow-out orifices 6—9 are provided alongside the path of the movable contact 2 by which they will be covered or uncovered in the travel of the same. In the position of the movable contact shown in Fig. 1 the orifices 8 and 9 are closed whilst the orifices 6 and 7 are uncovered. The chamber 3 is held against its supporting base plate 10 by means of bolts 11 and 12 that carry nuts against which pressure springs 13 and 14 rest which here constitute the spring members. The whole assembly is secured to one end of a wall insulator 15 by means of a lead-in rod 16.

Fig. 2 shows the device after the pressure within chamber 3 has reached a substantial value, that is, as long as a considerable current is flowing through the arc. The pressure drives the chamber downwards relatively to the fixed piston 4 while it stresses the springs 13 and 14. This

movement of the chamber uncovers the relief orifice 5 whilst the movable contact closes the blow-out orifice 6 partly and the blow-out orifices 7, 8 and 9 completely. Due to the fact that the displacement of the movable contact is designedly very slow as compared to that of the chamber, the movable contact will be substantially in the same position when the chamber, following the release in pressure, that is, as the current is nearing its zero value, is returned to its position shown in Fig. 1. It will be seen from this figure that the relief orifice 5 is closed whilst the blow-out orifices 6 and 7, formerly closed according to Fig. 2, are now uncovered, which means that maximum extinguishing action is exerted thereby upon the arc. If the blowing-out effect turns out to be insufficient, then the arc would be rekindled, with consequent increase in pressure and dashing of the chamber into the position shown in Fig. 2. Meanwhile, however, the movable contact 2 has moved further away, and the blow-out orifices 8 and 9 will in turn be uncovered when the chamber is returned the next time due to the pressure being relieved as a consequence of the current dropping almost to zero. This leads to the desired result that more blow-out orifices are uncovered when the current is substantially nil than when its value is comparatively high. Thus, the extinguishing effect is more powerful at minimum than at maximum current value. A further desirable result is obtained in that as long as a heavy current is flowing through the arc the gaseous products can escape easily through the relief orifice. Thus pressure developed is limited, which enables the chamber to be made considerably lighter in weight. Finally, a lesser amount of power will be consumed by the arc burning at lower pressure, which is particularly advantageous from the viewpoint of the stresses undergone by the switch.

Figure 3 illustrates an example of the application of this invention to a switch chamber with axial blow-out. The arrangement here is substantially the same as the one illustrated in Fig. 1 except that the blow-out orifices 6 and 7 are located coaxially with the movable contact. Underneath orifice 7 the interior of chamber 3 is enlarged so as to form a circular chamber 3' which is connected by a plurality of circumferentially arranged orifices 7' to the outside. It will be seen that just as in the embodiment illustrated in Fig. 1 a rise in pressure will cause the chamber 3 to move towards the movable contact, which results in the blow-out orifices 7 and 6 being closed and the relief orifices 5 uncovered, whilst in the reverse movement which closely precedes the dropping of the current to zero the blow-out orifices 7 and 6 are uncovered and the relief orifices 5 are closed again. The uncovering of orifice 7 is aided in its effect by the orifices 7' which are in connection with orifice 7 through the circular chamber 3'. When contact 2 moves downwards relatively to chamber 3 it uncovers first the orifice 7 at its upper edge and then establishes the connection of orifice 7 with the circular chamber 3' when the movable contact 2 passes the lower edge of orifice 7 which will put the orifices 7' into operation.

Figure 4 shows by way of example an application of the invention to a switch chamber in which the arc is blown out by a jet of liquid that rushes radially into a blow-out orifice. One single blow-out orifice 6 is provided here, forming the end of a bore 17 in the movable contact 2

which opens outside the chamber at its end remote from the blow-out orifice. The whole is immersed in a suitable liquid, for instance oil.

The operation of this device is as follows:

When the arc strikes within the chamber it becomes surrounded with a gas bubble into which the end of the movable contact 2 protrudes. The latter will protrude all the more as by the effect of the pressure set up by the gases chamber 3 moves towards said movable contact, most of the oil thus being carried with said chamber, which consequently is trapped in the bottom of the chamber from which it cannot escape through the orifice 6 since the latter emerges from the liquid. Therefore, the hot gases are free to escape through the relief orifices 5 as well as through orifice 6 which acts as an additional relief orifice and is made ineffective from the viewpoint of its extinguishing action. As the pressure is relieved due to the current drop the chamber is returned quickly together with the oil whose level follows integrally the displacements of the chamber. In the course of such ascending motion the orifice 6 is suddenly flooded by the oil which is rushed thereinto by the residual pressure, whereby it actually chokes off the arc just at that moment when it still carries a low current. Definitive extinction is thus secured and any kindling precluded. Grooves 18 of a greater or smaller depth and projections 19 located at a greater or shorter distance from the movable contact may be provided so that the oil can follow more readily the very swift movements of the chamber.

The chamber can more easily be taken to pieces where the arrangement shown in Figs. 5 and 6 is used. With this end in view the spring members, e. g. coils springs 13, act on bolts 11 which are formed with a neck portion 21 and a pair of shoulders 22, 23 shown at the left of Fig. 5 which is a fractional sectional view taken along line X-X of Fig. 6. When no pressure is prevailing in the chamber the shoulder 22 is held in engagement with the chamber by spring 13. Milled in the chamber-supporting plate are slots 20 through which the shoulders can move when a rotational movement is imparted to the chamber in the direction of the arrow F (Fig. 6). A latch 24 under the action of a spring 25 prevents any unintended loosening of the chamber from its supporting plate. When a pressure exists within the chamber the spring 13 is compressed by the amount necessary for such displacement; shoulder 22 disengages its seat but shoulder 23 still holds bolt 11 retained by plate 10. In order to take away the chamber it is only necessary to push the latch 24 aside and to swivel the whole against the direction shown by the arrow F.

I claim:

1. A circuit interrupter of the fluid blast type comprising a pressure pot; a stationary and a movable contact in said pot; a chamber forming part of said pot and arranged for to and fro movements in axial direction; a discharge aperture in said chamber arranged for being opened and closed during the to and fro movement of said chamber whereby the increase of the pressure in said pot is diminished when the current is in vicinity of its maximum; and blast apertures in the wall of said chamber located along the path of said movable contact whereby the blast discharge is diminished when the current is in vicinity of its maximum, and increased when the current approximates zero.

2. A circuit interrupter as claimed in claim 1,

said blast apertures being arranged transversely to the direction of movement of said movable contact.

3. A circuit interrupter as claimed in claim 1, said blast apertures being arranged longitudinally to the direction of movement of said movable contact.

4. A circuit interrupter of the fluid blast type comprising a pressure pot; a stationary contact and a hollow movable contact in said pot; a chamber forming part of said pot and arranged for to and fro movements in axial direction; a discharge aperture in said chamber arranged for being opened and closed during the to and fro movement of said chamber whereby the increase of the pressure in said pot is diminished when the current is in vicinity of its maximum; and a blast aperture in said hollow movable contact.

5. A circuit interrupter of the fluid blast type, comprising in combination, a pressure pot; a stationary contact in said pot; a movable contact in said pressure pot movable from a first position in contact with said stationary contact into a second position spaced from said stationary contact, and vice versa; a discharge aperture in said pressure pot arranged so as to be automatically opened when the pressure in said pressure pot increases beyond a predetermined value; and at least one blast aperture in said pressure pot arranged so as to be in open position only when said discharge aperture is closed and said movable contact is in the second position spaced from said stationary contact.

6. A circuit interrupter of the fluid blast type, comprising in combination, a pressure pot; a stationary contact in said pot; a movable contact in said pressure pot movable from a first position in contact with said stationary contact into a second position spaced from said stationary contact, and vice versa; a discharge aperture in said 40

pressure pot arranged so as to be automatically opened when the pressure in said pressure pot increases beyond a predetermined value; and at least one blast aperture in said pressure pot cooperating with said movable contact and arranged so as to be in open position only when said discharge aperture is closed and said movable contact is in the second position spaced from said stationary contact.

7. A circuit interrupter of the fluid blast type, comprising in combination, a pressure pot; a stationary contact in said pot; a movable contact in said pressure pot movable from a first position in contact with said stationary contact into a second position spaced from said stationary contact, and vice versa; a discharge aperture in said pressure pot arranged so as to be automatically opened when the pressure in said pressure pot increases beyond a predetermined value; and at least one blast aperture in said pressure pot located along the path of said movable contact and arranged so as to be in open position only when said discharge aperture is closed and said movable contact is in the second position spaced from said stationary contact.
